(57) **CLAIM**

The ornamental design for an electronic video game case, as shown and described.

DESCRIPTION

FIG. 1 is a right front perspective view of an electronic video game case showing my new design;

FIG. 2 is a left front perspective view of the invention illustrated in FIG. 1, shown with the front flap open, the bold broken lines representing environment and forming no part of the claimed design;

FIG. 3 is a front elevation view of the invention illustrated in FIG. 1;

FIG. 4 is a rear elevation view of the invention illustrated in FIG. 1;

FIG. 5 is a top plan view of the invention illustrated in FIG. 1;

FIG. 6 is a right elevation view of the invention illustrated in FIG. 1;

FIG. 7 is a left elevation view of the invention illustrated in FIG. 1; and,

FIG. 8 is a bottom plan view of the invention illustrated in FIG. 1.
